SURGICAL LEG SPLINT

Earl E. Longfellow, Warsaw, Ind., assignor to
Harry Herschel Leiter, Warsaw, Ind.

Application November 16, 1935, Serial No. 50,169

4 Claims. (Cl. 128—84)

This invention relates to improvements in surgical leg splints of a similar type to that set forth in my previous application, Ser. No. 720,581, now Patent No. 2,069,721, but differing therefrom in several particulars.

One of the objects of the present invention is the provision in a splint that has members that are respectively applied to an uninjured leg and the injured leg of a patient, of mechanism to permit rotative adjustment of both of said members as well as relative longitudinal adjustment thereof.

Another object is to provide a splint having members for connection with the uninjured and injured legs, having stirrups that are readily detachable from said members.

Other objects and advantages of the invention appear in the following description.

An illustrative embodiment of the invention is shown in the accompanying drawing, in which:—

Fig. 1 is a front elevation of a structure in which the invention is embodied, a portion being broken away; and

Fig. 2 is a top plan view projected from Fig. 1, certain parts being in horizontal section.

The illustrative embodiment of the invention includes in its structure a cross-head 1 provided at the ends thereof with corresponding rods 2 and 3, which rods extend in parallel relation with each other and at right angles with respect to the length of the cross-head. The lower ends of said rods project downwardly from said cross-head and are threaded to receive corresponding nuts 4, and have mounted thereon between said nuts and the cross-head a beam 5 that extends laterally in one direction. The beam has in one end portion thereof oppositely disposed arcuate slots 6 through which the lower ends of the rods 2 and 3 respectively extend whereby the cross-head is adapted to be adjusted rotatively upon an axis at right angles thereto relative to the beam.

Upon the end portions of the rods 2 and 3 that project upwardly from the cross-head is mounted a frame 7 that is slidable thereon longitudinally with respect to said rods. The frame 7 has a hook 8 adjacent its upper end that projects laterally from its outermost side and has connection with one end of a retracting spring 9. The cross-head 1 also has a projecting hook 10 that has connection with the outer end of said spring, which spring acts to restrain movement of the frame on said rods in the direction away from the cross-head. The frame has at its sides corresponding elongated guides 11 and 12 into which said rods loosely extend respectively. That por-

tion of the rod 3 that projects upwardly from the cross-head is threaded and has thereon an adjusting nut 13 located beneath the lower end of the guide 12 so that by turning the adjusting nut the frame 7 is longitudinally moved with respect to said rods in opposition to the action of the spring 9.

The upper end of the frame 7 preferably is arcuate and has secured thereon an U-shaped strip constituting a stirrup 14 that is detachably fastened to the frame preferably by means of screws 15.

The laterally extending end portion of the beam 5 has adjustably mounted thereon a bracket 16, there being a series of spaced apertures 17 in the beam for the reception of a securing bolt 18 that extends through the bracket and one or another of said apertures. The slot 19 in the bracket through which the beam extends is sufficiently large as to permit of limited tilting movement upon the axis of the bolt and also the lower end of said bracket, being closed, prevents inadvertent disconnection of the bracket from the beam when the bolt 18 is removed to permit adjustments therebetween. The upper end of the bracket has a threaded stud 20 upon which is adjustably secured a clamp 21 provided with a tightening screw 22 to secure the clamp against rotative movement relative to the stud. The clamp has at its upper end an arcuate extension 23 to the sides of which are removably secured corresponding separable strips 24 that extend in parallel relation with each other and constitute a second stirrup. The strips 24 are individually removable from said extension upon removal of screws 25 by which said strips are secured to the extension on the outer faces thereof. Each strip has made therein a series of perforations 26 for the reception therethrough of a skeletal pin 27 which is adapted to be inserted transversely with respect to said stirrup.

Operation

In use, the stirrup 14 is placed astride of the lower extremity of the uninjured leg of the patient (not shown). The sides of the stirrup are then preferably encased together with the uninjured leg by applying a plaster cast in the usual manner. The frame 7 is thus firmly held attached to the uninjured leg. The strips 24 of the other stirrup are then placed astride of the injured leg and, if the surgeon elects to apply skeletal treatment, a pin preferably of the Steinmann type is inserted through the perforations 26 in said strips and the injured leg so as to engage the bone frag-

ment therein. A plaster cast is then applied so as to encase the strips, the projecting ends of the pin and the injured leg, in the usual manner. The bracket 16 is then adjusted upon the beam to such position as to afford the desired angulation or spread between the legs of the patient. The clamp 21 is then loosened on the stud by turning the screw 22 to permit movement of the clamp to secure the desired rotative adjustment of the leg, after which the screw is tightened so that adjustment of the leg is secured in that respect.

After the legs have been secured in their respective stirrups and the plaster casts have set. The nuts 4 are loosened so as to permit adjustment of the cross-head with respect to the beam 5. In this manner extroversion and introversion of the uninjured leg is readily accomplished by maneuvering it into a good and comfortable position, after which the nuts 4 are tightened. Then, by turning the adjusting nut 13, movement is imparted to the cross-head 1 and the beam 5 away from the frame 7 in opposition to the restraint of the spring 9, and in this manner is applied extension with respect to the injured leg and counter-extension with respect to the uninjured leg.

A valuable feature of the invention is the adjustments of the supporting members for the stirrups with respect to their connecting beam that affords advantageous positioning of the uninjured as well as the injured leg.

And another feature of value is that the strips that form the stirrups are connected with the frame 7 and extension 23 respectively in such manner as to admit of their detachment therefrom without discomfort to the patient.

I claim:—

1. In a surgical splint having members applicable respectively to an uninjured and injured leg of a patient, a cross-head having parallel rods located respectively at its ends that extend at right angles thereto, a beam provided with arcuate slots through which the lower ends of said rods extend and permit relative adjustment of said cross-head and beam transversely to said rods, means for securing said beam in its adjusted positions, a frame having guides at its sides into which the upper end portions of said rods slidably extend, an adjusting nut having threaded relation with one of said rods located between said cross-head and frame, a retracting spring the ends of which are connected respectively with said cross-head and frame, a stirrup removably secured to

said frame, a bracket adjustably secured on said beam, a clamp rotatively adjustable on said bracket provided with an extension, and strips removably secured respectively upon the outer sides of said extension constituting a second 5 stirrup.

2. In a surgical splint having members applicable respectively to uninjured and injured legs of a patient, a frame provided with a stirrup and having longitudinal parallel guides, a cross-head 10 having parallel rods that extend into said guides to permit longitudinal adjustment of said frame thereon, a beam connected with said cross-head so as to permit relative adjustment of said cross-head and beam transversely to said rods, means 15 for securing said beam in its adjusted positions, means for moving and securing said frame adjustably on said rods relative to said cross-head, a retracting spring connecting said frame and cross-head, a bracket secured on said beam, a 20 clamp rotatively adjustable on said bracket, and strips removably secured in connection with said bracket constituting a second stirrup.

3. In a surgical splint having members applicable respectively to uninjured and injured legs of a 25 patient, a frame provided with a stirrup and having longitudinal parallel guides, a cross-head having parallel rods that extend into said guides to permit longitudinal adjustment of said frame thereon, a beam connected with said cross-head 30 so as to permit relative adjustment of said cross-head and beam transversely to said rods, means for securing said beam in its adjusted positions, means for moving and securing said frame adjustably on said rods relative to said cross-head, 35 and a second stirrup having an adjustable connection with said beam.

4. A surgical splint applicable to uninjured and injured legs of a patient, said splint having a member including a stirrup for attachment to the 40 uninjured leg and provided with a laterally extending beam, another member including a stirrup for attachment to the injured leg and provided with a supporting bracket therefor, said bracket having an opening therein, through which said 45 beam extends, proportioned so as to permit limited tilting movement of said bracket on said beam, the bottom of said bracket being closed to prevent inadvertent disconnection of said bracket from said beam, and means for securing said bracket 50 adjustably on said beam.

EARL E. LONGFELLOW.
